[57] CLAIM

The ornamental design for a grid-like guard for the
front of a portable heater, as shown and described.

DESCRIPTION

FIG. 1 is a top plan view of a grid-like guard for the
front of a portable heater, showing our new design;
FIG. 2 is a front elevational view thereof;
FIG. 3 is a left end elevational view thereof;
FIG. 4 is a rear elevational view thereof;
FIG. 5 is a right end elevational view thereof;
FIG. 6 is a bottom view thereof;
FIG. 7 is a top plan view of a second embodiment of a
grid-like guard for a portable heater;
FIG. 8 is a front elevational view thereof;
FIG. 9 is a left end elevational view thereof;
FIG. 10 is a right end elevational view thereof;
FIG. 11 is a rear perspective view thereof.

FIG. 1.FIG. 2.FIG. 4.

FIG. 3.

FIG. 5.

FIG. 6.

FIG. 7.

FIG. 8.

FIG. 11.

FIG. 10.

FIG. 9.
